Primary Examiner — Carla Jobe Wright

(57) **CLAIM**

The ornamental design for an electronic device shell with cover, as shown and described.

DESCRIPTION

FIG. 1 is a front perspective view of an electronic device shell with cover;

FIG. 2 is a rear perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof;

FIG. 9 is a front perspective view showing the electronic device shell with cover in another configuration;

FIG. 10 is a rear perspective view thereof;

FIG. 11 is a front elevation view thereof;

FIG. 12 is a rear elevation view thereof;

FIG. 13 is a left side elevation view thereof;

FIG. 14 is a right side elevation view thereof;

FIG. 15 is a top plan view thereof; and,

FIG. 16 is a bottom plan view thereof.

Broken lines shown in the drawings depict stitching which is part of the claimed design.

1 Claim, 14 Drawing Sheets
